UNITED STATES PATENT OFFICE.

HENRY CHARLES SPEIGHT, OF BRADFORD, ENGLAND.

DOFFING MECHANISM FOR SPINNING-FRAMES AND THE LIKE.

1,350,578.

Specification of Letters Patent. Patented Aug. 24, 1920.

Application filed April 11, 1919. Serial No. 289,419.

To all whom it may concern:

Be it known that I, HENRY CHARLES SPEIGHT, subject of the King of Great Britain and Ireland, residing at Upper Croft 5 Mills, Bowling Back Lane, Bradford, in the county of York, England, have invented new and useful Improvements in and Relating to Doffing Mechanism for Spinning-Frames and the like, of which the following is a 10 specification.

This invention relates to improvements in doffing mechanism for spinning frames, and the like, and my object is to arrange and construct certain mechanism to be applied to 15 spinning frames and the like, in such wise that full bobbins or the like are expeditiously removed from their spinning position and empty ones moved into place, the arrangement generally comprising a sliding 20 front bar so mounted as to be given a rising and falling motion, the said bar carrying clips or receptacles to engage, receive, hold, and deliver bobbin or like flanges, and these clips may be moved in, to allow one set to 25 embrace, hold or engage the said flanges, and at the desired time be moved sidewise to deposit the other set carrying empty bobbins or the like in position to be engaged by the spindles and so be held ready for spinning. When the clips are withdrawn 30 toward the front of the frame, one clip of each set will be empty and the other will carry the full bobbin or like. For the next doff the sidewise movement of the clip or like 35 carrying device will be reversed.

In the case of a ring spinning frame some means are desired to lead the yarn to the back of the tube or like and to the base thereof, and to this end the eyes or twizzles are 40 mounted in connection with a bar which may through suitable gear be lowered, and each eye or twizzle or group thereof may be so mounted that they may have a tilting action to clear the sides of the spool or like as 45 they descend.

I am aware that it has heretofore been proposed to carry means for supporting both full and empty bobbins on or in connection with a sliding rod mounted in front of the 50 frame in such wise that the said means may have a rising and falling motion in addition to a movement toward or away from the spindle, either by being turned through an arc or moved laterally. In these cases however 55 some device has been necessary to hold the bases of the bobbins such as a series of

points or fingers swung or moved under the bobbins either from behind or in front of the spindles. These arrangements are generally suitable to my purpose, but I wish it 60 to be understood that I make no claim to same.

In describing my invention in detail reference is made to the accompanying sheets of drawings, similar letters indicating similar 65 parts in which:—

Fig. 1 represents a sectional elevation showing my improvements.

Fig. 2 represents a detail of the moving eye board hereinafter described. 70

Fig. 3 represents a plan view of a portion of a "ring" frame with my improvement added thereto.

Fig. 4 represents a section through a bobbin carrier clip. 75

Fig. 5 represents a view of a bobbin or like carrier, and

Fig. 6 represents a view of a bobbin or like carrier as used for cap spinning.

To carry my improvement into effect, I 80 will describe same with reference to a ring spinning frame to which it is especially adapted, but I wish it to be understood I may apply it to other frames and make the necessary modifications to meet the varying 85 requirements, removing caps and fliers in any suitable or known manner and providing the bobbins, tubes, or spools, with a suitable flange to engage the holding device. It being intended to adapt the full and empty 90 bobbin carriers as equivalent to pegs or the like as hereinafter set forth.

Mounted in front of the frame and capable of a rising and falling motion through suitable gearing is a supporting member 95 or members A adapted to carry a sliding bar or rod B which along with the supporting member may also be moved toward and away from the spindles or spindle rail. This sliding bar B carries duplicate carriers, 100 holders, or clip like devices C Fig. 4 for each spindle, such device being formed by preference in the shape of spring acting forks C', each of these spring forks being adapted to engage the edges of a flange F 105 formed on a tube F' adapted to fit over the spindles S toward the whirl; in other words the flanges and tubes form a short hollow spindle and are adapted to carry the spools, tubes or bobbins T, the upstanding portion F' in some cases being tapered. One of 110 these devices will be mounted over each

whirl or on each spindle and one will be carried in one of the forks or holders C leaving an empty holder opposite each spindle as shown in Fig. 3.

5 The twizzles or eyes E Figs. 1, 2 and 3 through which the yarn is passed centrally above the spindle and tubes or like thereon, are mounted on a bar E' which by means of suitable mechanism may be lowered and 10 raised, but in order to clear the spools or like as they descend the eyes E are made to tilt either by gravity, by a spring, or suitable catches, arranged in connection with the framework of the machine. They may tilt 15 individually or "en masse" as shown. Thus when the eyes E are lowered the yarn is led to the back of the tube, spool, or like. If tilted by gravity or weights, a bar toward the top, or catches at the side of the machine, 20 will be provided to cause them to resume their normal acting position when they are brought back to spinning position as herein-after described. Suitable means will be provided for lowering the ring or lifter rail 25 R means to this end being common to the frames.

The eyes E are mounted on a bar E' and are hinged thereto as at E² and to give them play a spring E³ connects two portions as 30 shown in Figs. 1 and 2. The bar E' operates in slides E⁴ carried from the usual board D in any convenient manner, and a chain or like connection E⁵ leads from the bar E' over a pulley E¹¹ to a suitable shaft or drum 35 thereon E⁶ which is turned as desired by a handle or lever E⁷ Fig. 1. A cam projection E⁸ Figs. 1, 2 and 3 engages a cam or pulley such as E⁹ attached to the sides of the frame and a weight E¹⁰ is attached to the bar E' 40 in any suitable position to cause it to tend to tilt so that when the bar is lowered the weight E¹⁰ causes same to tilt and when reversed the projection E⁸ makes contact with the roller or pulley E⁹ and the bar and eyes 45 resume their normal position. The bearings of the bar E' are suitably formed to allow of the turning or tilting movement.

I have not gone into a detailed description of the rising and falling movement and 50 lateral movement of the carriers C but have shown a means in the drawings which is well known.

The carriers C are attached to the sliding bar in any convenient manner, one means 55 being illustrated. These carriers comprise forked ends C² Fig. 3 each having a lower tray like edge C³ Figs. 1 and 4 and mounted over these tray like edges are forks C' pivoted toward the front edge as at C⁴ Fig. 4 60 and terminating in a spring acting device such as C⁵. The flange F of the bobbin or like supporting device will pass between the forks C' and the edge C³ and when the forks are pressed up against or toward the 65 spindle the flange will be securely held.

Similarly when a flange and supporting device is in a clip and the spindles enter same, on the withdrawal of the clip the flange and device will remain on the spindle.

In operation the first step is to lower the 70 ring rails R to their lowest position in the usual manner, before stopping spinning, so that the end is wrapped round the spindle or whirl below the tubes or bobbin, and next to lower the eyes or twizzles E by 75 means of handle E' till they are about opposite the rings, the eyes tilting to clear the bobbins or like as they descend. The holders C in front of the machine will be opposite the base or flange F of the tubes F' 80 before mentioned, and an empty holder will be opposite the full spool or like as shown in Fig. 1. The holders C are moved by handle B' Fig. 3 so adjusted that the correct movement is given to move the holder with the new spool or like thereon 85 opposite and over the now empty spindle. 90 The front rail and holders are next lowered and the holders withdrawn leaving in each case the full spool in one holder and nothing in the other. The upward movement of the full spool in the holder will 95 break or sever the yarn and leave an end engaging the whirl which may be suitably notched.

The eyes or twizzles are returned to their 100 normal position and spinning goes on. In setting, the full spool or like is taken from the false spindle F' and an empty tube or like placed thereon and for the next doff the movements are as before with the exception that the sliding bar is moved in the 105 other direction.

It will be seen that doffing may be expeditiously effected and the parts are simple in action, and while, as before mentioned the motion is one which is especially 110 adapted to ring frames the use of holders or clips along with the false spindles or pegs substantially as described may with advantage be applied to other machines, coupled with means for guiding the yarn to 115 a suitable position for breaking or severing. For example for cap frames, which will have the usual cap holding devices, the tube T' Fig. 6 will be separate from the whirl W and will have a flange F' corresponding to 120 the flange F and means such as engaging lugs W' and T' to facilitate driving. The flange F' will be embraced similarly to the flange F and the tubes T will be duplicated for each spindle.

I declare that what I claim is:—

1. The combination with a spinning machine having a row of spindles, of doffing mechanism, comprising a pair of holders for each spindle, all of said holders being 130

located in longitudinal alinement and adapted for reciprocatory movement vertically, longitudinally, and transversely with relation to the row of spindles, whereby the 5 holders are always in vertical position.

2. The combination with a spinning machine having a row of spindles, of doffing mechanism, comprising a pair of holders for each spindle, all of said holders being 10 located in longitudinal alinement and adapted for reciprocatory movement vertically, longitudinally, and transversely with relation to the row of spindles whereby the holders are always in vertical position, and 15 independent means for moving said holders in either of said directions.

3. In doffing mechanism for spinning frames, an eye or like board or carrier capable of a rising and falling motion having 20 means for tilting the eyes or twizzles to clear the bobbin or the like during the downward motion and means for returning the eyes to their normal position during the ascending motion substantially as described.

25 4. The combination with a spinning machine having a row of spindles, of doffing

mechanism, comprising a pair of holders for each spindle, all of said holders being located in longitudinal alinement and adapted for reciprocatory movement vertically, longitudinally, and transversely with relation to the row of spindles, a pivotally mounted thread guide adapted for vertical reciprocatory movement, and means for swinging said guide on its pivot during 30 such movement.

5. In a doffing mechanism for spinning machines having a row of spindles, the combination of a plurality of tubes each adapted to carry a bobbin, a support for 40 each of said tubes movable in straight lines in three directions relatively to the spindles for removing the bobbins therefrom while retaining the holders in vertical position at all times and coöperating means carried by 45 the tubes and supports for flexibly retaining the tubes on said supports.

In testimony whereof I have signed my name to this specification.

HENRY CHARLES SPEIGHT.
